REMOTE-CONTROL VALVE

Loyd A. Ward, Jackson, Mich., assignor to
 Tomkins-Johnson Company, Jackson, Mich., a
 corporation of Michigan

Application March 7, 1940, Serial No. 322,657

16 Claims. (Cl. 121—46.5)

The present invention relates to remote control valves and more particularly to a remote control valve of the character wherein a distributing piston is reciprocated under manual control by fluid pressure within a cylinder to direct a fluid under pressure to a controlled cylinder to move a controlled piston therein from one end to the other.

In known remote control valves of the character described, an example of which is disclosed in Patent No. 1,791,613 to Clay, there is a disadvantage in that it is not possible to stop a controlled piston midway between the ends of its stroke. The reason for this is that since the distributing piston is fluid actuated, when once it is moved, it continues to move to the end of its travel and remains in that position continuously delivering pressure fluid to one end of the controlled cylinder. According to the present invention, this disadvantage is eliminated by providing centering mechanism for automatically centering the distributing piston, at controlled times, to a position where it does not deliver pressure fluid to either end of the controlled cylinder. With such a remote control valve, the controlled piston may be moved to any position along its stroke and maintained in that position with the controlled cylinder under pressure.

An object of the invention is to provide a remote control valve having a distributing piston which may be automatically centered at the will of the operator.

Another object of the invention is to provide a remote control valve having a distributing piston which is actuated by the release of pressure fluid and which returns to a neutral, inactive position upon closing the fluid pressure releasing means.

A further object of the invention is to provide a remote control distributing valve actuated by the release of pressure fluid, which is automatically centered by auxiliary pistons working in auxiliary cylinders which carry the released pressure fluid.

A still further object of the invention is to provide a remote control distributing valve automatically centered by auxiliary pistons working in auxiliary cylinders, the valve being moved by full line pressure overcoming the action of a predetermined one of said auxiliary pistons.

A still further object of the invention is to provide a remote control valve which is quick in operation and which can be manipulated to stop a controlled piston at an intermediate portion of its stroke.

A still further object of the invention is to provide a remote control distributing valve having a reciprocating piston provided with exhaust ports in the surface thereof wherein the reciprocating piston is balanced against side thrust by

exhaust fluid in the exhaust ports that are in its surface.

These and other objects will be apparent from the following specification when taken with the accompanying drawings in which:

Fig. 1 is a vertical section through a remote control valve according to the present invention, showing in diagrammatic form a cylinder and piston controlled by the remote control valve and in elevation pressure releasing control valves,

Fig. 2 is a section on the line II—II of Fig. 1,

Fig. 3 is a section on the line III—III of Fig. 1,

Fig. 4 is a vertical section through one of the pressure releasing valves showing details thereof,

Fig. 5 is a partial vertical section of another form of the invention wherein the control valve is shifted by means of fluid pressure rather than by exhausting fluid pressure,

Fig. 6 is a section on the line VI—VI of Fig. 5, and

Fig. 7 is a section of an alternative form of valve that may be used for controlling the main line pressure for actuating the controlling valve.

Referring particularly to the drawings, the reference character 1 indicates the remote control valve body having an outside portion 2, preferably of cast iron, and a liner 3, preferably of bearing bronze surrounding a chamber 4. In the body 1 is an inlet port 5, outlet ports 6 and 7, and exhaust ports 8 and 9. Reciprocably slideable in the chamber 4 is a distributing piston 10 provided with a distributing chamber 11 open on one side to the interior wall of the body 1 opposite the inlet 5, as shown particularly in Figs. 1 and 3. Also in the piston 10 is a distributing port 12 providing a communication from the distributing chamber 11 to the opposite side of the piston 10 and moving into and out of communication with the outlet ports 6 and 7 as the piston reciprocates in the chamber 4. It will be appreciated that the distributing chamber 11 is a part of the distributing port 12. Providing communication between the opposite ends of the chamber 4 and the distributing chamber 11 are leakage ports 15 and 16 of restricted diameter for equalizing the pressure at the ends of the chamber 4 with the pressure of the distributing chamber 11 which is the inlet pressure.

Caps 17 and 18 at opposite ends of the body 1 are secured thereto by the cap screws 19 or their equivalents. The caps 17 and 18 provide closures for the ends of the chamber 4 and are provided with auxiliary cylinders 20 and 21. Within the auxiliary cylinders 20 and 21 are auxiliary pistons 22 and 23 respectively. The pistons 22 and 23 are provided with stems or rods 24 and 25 respectively which project into opposite ends of the chamber 4 through bushings 26 and 27 and packings 28 and 29. Extending axially through the rods 24 and 25 are ports 35 and 36 of somewhat larger di-

ameter than the leakage ports 15 and 16. In order to provide a communication with the chamber 4 through the rods 24 and 25 at such times as the ends of the ports 35 and 36 may be closed by the distributing piston 10, there are provided in the rods 24 and 25 additional ports 37 and 38 in the portion of the rods 24 and 25 within the chamber 4, communicating with the ports 35 and 36 and normal thereto. As the ports 37 and 38 extend through the rods 24 and 25 and the ports 35 and 36, their areas need be only one-half of those of the ports 35 and 36.

The outer ends of the cylinders 20 and 21 are provided with exhaust ports 39 and 40 respectively and are connected by means of conduits 45 and 46 respectively to exhaust valves 47 and 48, the construction of the exhaust valves being shown particularly in Fig. 4 wherein the exhaust valve 47 is shown in cross-section.

The exhaust valves each comprise a body having an inlet 49 and an outlet 50. Within the body is a removable seat member 51 bearing against a packing 52 which in turn is seated on a shoulder 53. Bearing against the seat 51' of the seat member 51 is a valve member 54 having a stem 55 and a manually actuatable push button 56. A helical spring 57 maintains the valve member 54 against its seat 51' and the gland packing 58 under compression to prevent the leakage of pressure fluid past the stem 55. As appears particularly from Fig. 4, communication from the inlet 49 to the outlet 50 is under the control of the valve member 54. In normal position the spring 57 prevents communication between the inlet 49 and the outlet 50, but upon pressure being applied to the push button 56, the spring 57 is compressed, the valve member 54 is moved away from the seat 51' and communication between the inlet 49 and the outlet 50 is established. The outlet 50 opens to the atmosphere either directly or through a suitable conduit.

In order to move the distributing piston 10 from one end of the chamber 4 to the other, pressure fluid in the end of the chamber 4 to which it is desired to move the distributing piston 10 is exhausted by exerting pressure on the appropriate push button 56. As shown in the drawings, the distributing piston 10 is at the right end of the chamber 4 and the push button 56 of the exhaust valve 48 is depressed. The depressing of the push button 56 opens the exhaust valve 48 to exhaust pressure fluid from the right end of the chamber 4 through the ports 36 and 38 in the rod 25, the cylinder 21, the exhaust port 40 and the conduit 46. Since the pressure at the right end of the chamber 4 is reduced, the pressure fluid at the left end of the chamber 4 expands to drive the distributing piston 10 to the right. The distributing piston 10 will remain at the right end of the chamber 4 so long as the exhaust valve 48 remains open. It will be observed that when the distributing piston 10 is at the right end of the chamber 4, the rod 25 and its piston 23 are at the right end of the auxiliary cylinder 21, having been moved to that position under the action of the distributing piston 10. However, should the exhaust valve 48 be closed, then pressure fluid from the inlet 5 and the distributing chamber 11 will flow through the leakage port 16, the ports 38 and 36 in the rod 25 and into the auxiliary cylinder 21. Then, since the pressure at both ends of the distributing piston 10 is equalized by the flow of the pressure fluid from the distributing chamber 11 through the leakage ports 15 and 16, and since the effective area of the auxiliary piston 23 in

the auxiliary cylinder 21 is greater than the effective area of the rod 25 in the chamber 4, the unbalance of pressure will cause the auxiliary piston 23 to move to the left until it abuts against the shoulder 60 in the cap 18. In order to permit free movement of the auxiliary pistons 22 and 23 in the auxiliary cylinders 20 and 21, there are provided at the inner ends of the auxiliary cylinders 20 and 21, vents 61 and 62. As will be observed from Fig. 1, the length of the rods 24 and 25 are such that when they are projected to their full length in the chamber 4, the distributing piston 10 is at its central position so that the distributing port 12 is midway between the outlet ports 6 and 7 and does not communicate with either of them. The central position of the distributing piston 10 is shown in dotted outline in Fig. 1.

As shown particularly in Fig. 3, when the distributing piston 10 is at the right end of the chamber 4, the pressure fluid from the inlet port 5 passes through the distributing chamber 11, the distributing port 12 and the outlet port 7 to the conduit 65 communicating with one end of a controlled cylinder 66. Pressure fluid from the inlet 5 then forces the controlled piston 67 in the controlled cylinder 66 to the right. It will be understood that the piston rod 68 operated by the piston 67 is suitably connected to and operates a machine not shown.

As the piston 67 is being moved to the right, exhaust pressure fluid in the right end of the cylinder 66 is forced through the conduit 69, to the outlet port 6 which as shown in Figs. 1 and 2 is connected to the exhaust port 8 by means of an exhaust groove 70 in the surface of the distributing piston 10. When the distributing piston 10 is moved to the left of the chamber 4 by opening the exhaust valve 47 to exhaust pressure fluid from the left end of the chamber 4 through the ports 37 and 35 in the rod 24, the cylinder 20, the exhaust port 39 and the conduit 45, the distributing port 12 in the distributing piston 10 moves into register with the outlet port 6, and at the same time, an exhaust groove 71 in the distributing piston 10 moves to provide a communication between the outlet port 7 and the exhaust port 9. Thus in left position, the distributing piston 10 distributes pressure fluid from the inlet port 5 through distributing chamber 11 and distributing port 12 to the outlet port 6, from which pressure fluid is conducted by the conduit 69 to the right end of the cylinder 66 to drive the piston 67 to the left. As the piston 67 is moving to the left, the exhaust pressure fluid at the left of the cylinder 66 will be forced through the conduit 65 to the outlet port 7 from which it is conducted by the exhaust groove 71 to the exhaust port 9. As soon as pressure on the push buttons 56 of the exhaust valve 49 is released, the distributing piston 10 centers under the action of the auxiliary piston 22 and the rod 24, operating in the same manner as the auxiliary piston 23 and rod 25. In using the remote control valve of the present invention it will be understood that valves may be used to control the exhausting fluid from the exhaust ports 8 and 9 to control the speed of movement of the piston 67 as is well known in the art.

Should it be desired to position the operated piston 67 in some particular intermediate portion of the operated cylinder 66, the appropriate exhaust valves 47 and 48 are opened until the piston 67 is in its desired position and then closed. The unbalance of pressure between the

pistons 22 and 23 and their respective rods 24 and 25 will cause them to move inwardly of the chamber 4 and thus center the distributing piston 10 so that the distributing port 12 is out of register with the outlet ports 6 and 7 and the exhaust grooves 70 and 71 are out of register with the exhaust ports 8 and 9 respectively. At the same time the pressure fluid in both ends of the cylinder 66 is sealed against exhausting by the surface of the distributing piston 10 closing 10 the inner ends of the outlet ports 6 and 7, as shown particularly in Fig. 1.

In order to maintain the distributing piston 10 against rotation with respect to the body 1, there is provided in one side of the distributing piston 10 a groove 73 into which is projected a pin 74 disposed in a bore 75 in the body 1. Thus the distributing piston 10 may reciprocate in the chamber 4 without rotation. In order to prevent any lateral thrust by exhaust fluid that may be 20 under pressure in the exhaust grooves 70 and 71, the distributing piston 10 is provided with circumferential grooves 78 and 79 which include the exhaust grooves 70 and 71. In this manner the exhaust fluid entering the exhaust grooves 70 and 71 is permitted to pass entirely about the distributing piston 10 to completely balance any pressure in the exhaust grooves 70 and 71 that might cause a lateral thrust against the piston 10 and prevent easy reciprocation thereof. In order to facilitate the mounting of the body 1 on some suitable bracket or support, there are 30 provided bores 80.

While the push buttons 56 in the exhaust valves 47 and 48 have been described as manually actuatable, it will be understood by those skilled in the art that either one or both of these push buttons may be automatically actuated, as, for instance, by an arm projecting from some moving part of a machine to provide an automatic sequence of operation. It will be further understood that an advantage of the present construction resides in quicker operation. When the valve is being operated as prior art valves, in that the distributing piston 10 is moved completely to one end or the other of the chamber 4, upon release of the push button 56, which caused the movement of the distributing valve 10, the distributing valve 10 will automatically move to its central position as in the manner above described. Then when it is desired to move the distributing valve to move the controlled piston 67 in the opposite direction, the distributing valve 10 will have to move only from its central position to the opposite end of the chamber 4 rather than from one end of the chamber 4 to the other end thereof.

The foregoing form of the invention is for remote controlling when the pressure releasing valves 47 and 48 are a relatively short distance away from the fluid distributing valve. In practice this distance should not be over 15 feet. When the distance is greater than 15 feet, the frictional losses in the pressure releasing line are so great as to make the operation sluggish or impossible. Therefore, in such cases, it is necessary to employ direct fluid pressure for shifting the distributing piston 10. An adaptation of the form of the invention disclosed in Figs. 1 through 4, for shifting the piston 10 by 70 line pressure, is disclosed in Figs. 5 and 6 wherein the construction is substantially the same with the exception that from the structure of Figs. 1 through 4, there have been omitted the exhaust ports 39 and 40, the leakage ports 15 and 16 in 75

the piston 10, and the ports 35, 36, 37 and 38 in the auxiliary piston rods 24 and 25.

The auxiliary pistons 22 and 23 are urged to their inner positions by line pressure from the inlet port 5. The line pressure to the auxiliary cylinder 20 is conducted by ports in the body from the inlet port 5, comprising a port 85 extending laterally from the inlet port 5, a port 86 extending vertically, a port 87 extending longitudinally the full length of the body 1, and a port 88 extending laterally from the port 87 to the auxiliary cylinder 20. The line pressure is conducted to the auxiliary cylinder 21 by ports 85, 86, 87 and a port 89 extending laterally from the port 87 to the auxiliary cylinder 21. Thus there is continuous line pressure exerted against the outer ends of the auxiliary pistons 22 and 23 to yieldingly urge their respective auxiliary piston rods 24 and 25 inwardly against the ends of the distributing piston 10 to center it in the chamber 4.

In order to provide metal through which the port 87 may extend beyond the ends of the body 1, the caps 17 and 18 are provided with ridges 90, 25 as shown particularly in Fig. 6.

Communicating with the chamber 4 at one end is a port 91, and at the other end a port 92. By directing pressure fluid from the inlet conduit 93, which communicates with the inlet port 5, through the port 91 or the port 92, the distributing piston 10 may be moved to the right or the left of the chamber 4 as desired. The inlet conduit 93 is connected to the port 91 by a conduit 94 in which is a normally closed valve 95, and the port 92 is connected to the inlet conduit 93 by a conduit 96 in which there is a normally closed valve 97. The valves 96 and 97 are under the control of push buttons 98 and 99 respectively, and may be identical in construction with the valve 47, disclosed in Fig. 4. Vents 105 and 106 are provided at the ends of the distributing chamber 4 for permitting free movement of the distributing piston 10 therein.

In order to operate the form of the invention disclosed in Figs. 5 and 6, one or the other of the valves 95 and 97 is opened by pressing on the push buttons 98 or 99 respectively. Should it be desired to move the distributing piston 10 to the right, as shown in Fig. 5, the push button 98 is 45 depressed to open the valve 95 to permit the passage of pressure fluid from the main conduit 93 through the conduit 94 to the port 91 and from it into the left end of the chamber 4. Since the cross-sectional area of the distributing piston 10 in the chamber 4 is greater than that of the auxiliary piston 23 at the opposite end of the body 1, the distributing piston 10 will move to the right, the pressure fluid in the right end of the chamber 4 escaping through the vent 106. It will be understood that since the area of the port 91 is greater than that of the vent 105 communicating with the left end of the chamber 4, the escape of pressure fluid through the vent 105 will have no effect on the action of the pressure fluid in moving the distributing piston 10 to the right.

As soon as pressure on the push button 98 is released, pressure fluid to the port 91 is cut off and the pressure in the left end of the chamber 4 escapes through the vent 105. Also, since the auxiliary cylinder 21 is under full line pressure through the ports 85, 86, 87 and 89, the auxiliary piston 23 will move the auxiliary piston rod 25 to the left to center the distributing piston 10 as shown in dotted outline in Fig. 5.

Should it be desired to move the distributing piston 10 to the left, as viewed in Fig. 5, pressure on the push button 99 will open the valve 97 to permit the flow of pressure fluid from the main pressure fluid inlet conduit 93 through the conduit 96 and valve 97 to the port 92 at the right end of the chamber 4. In this case the movement of the distributing piston 10 to the left and its return to center position corresponds to the movement in the opposite direction as previously explained. It will be understood that when the distributing piston 10 moves to the right or to the left, it is for the purpose of directing pressure fluid from the inlet port 5 through the distributing chamber 11 and one or the other of the outlet ports 6 and 7, as described in the explanation of the operation of the form of the invention disclosed in Figs. 1 through 4.

As explained above, when pressure fluid is being directed into the chamber 4 through the port 91 or 92, there is a leakage through the vents 105 or 106 respectively. This leakage is not objectionable when it is unnecessary to hold the distributing piston 10 at one end or the other of the stroke for substantial periods of time. However, when such a substantial holding is required the vents 105 and 106 may be dispensed with and the valves 95 and 97 each replaced by a valve of the character disclosed in Fig. 7, which includes a vent.

As shown, the valve in Fig. 7 is connected in the conduit 94, thus replacing the valve 95. The valve is provided with a body 107 and a valve member 108 seating against a seat 109. The valve member 108 is movable by a stem 110 to which is connected a push button 111 and is urged against its seat 109 by a spring 112, disposed between the push button 111 and the gland nut 113. In normal operation, pressure fluid enters the valve through the port 114 and leaves it through the port 115. The valve stem is also provided with a valve member 120 for seating against a seat 121. The valve member 120 and its seat 121 control the flow of the exhaust fluid through the vent 122.

In the operation of the valve disclosed in Fig. 7, pressure fluid is conducted to the inlet port 114 by the conduit 94 from the main pressure fluid supply 93. When the push button 111 is depressed, the valve member 108 moves away from its seat 109 to permit the passage of pressure fluid from the inlet port 114 through the outlet port 115 from which it is conducted by the conduit 94 to the port 91 communicating with the chamber 4. At the same time the valve member 120 is urged against the seat 121 to prevent the escape of pressure fluid through the vent 122. When pressure is removed from the push button 111, the spring 112 moves the valve member 108 upwardly against its seat 109, and at the same time moves the valve member 120 upwardly away from its seat 121 to establish a communication between the outlet port 115 and the vent 122. In this way, as soon as pressure fluid is cut off from the port 91 communicating with the chamber 4, a vent through the portion of the conduit 94 between the port 91 and the outlet port 115, and the vent 122 is provided, thus exhausting pressure fluid from the left end of the chamber 4 as viewed in Fig. 5. It will be understood that when both the vents 105 and 106 are dispensed with, both valves 95 and 97 are replaced by valves of the character disclosed in Fig. 7, for removing pressure fluid from the respective ends of the

chamber 4 upon the cutting off of pressure fluid thereto.

While the distributing valve, according to the present invention, is employed particularly for distributing compressed air, it will be understood that it may be employed for distributing other types of pressure fluid, as for instance, hydraulic fluid commonly employed in hydraulic actuating mechanism.

10 Having thus described my invention, what I desire to secure by Letters Patent and claim:

1. A control valve for distributing fluid under pressure comprising a body having a chamber therein, a fluid distributing piston slidably disposed in said chamber, a conducting chamber in said piston, an inlet port in said body communicating with said conducting chamber, a conducting port in said piston communicating at one end with said conducting chamber and at the other 20 end terminating at a sliding surface of said piston, a pair of spaced outlet ports in said body communicating with said first chamber in the path of movement of said conducting port, differential fluid pressure means to move said distributing piston to bring said conducting port into communicating relation with the desired one of said outlet ports, fluid actuated means to automatically center said distributing piston in a position in which it communicates with neither of 30 said outlet ports and continuous fluid connections between the fluid to be distributed and said fluid actuating means for providing pressure fluid for actuating the same, said fluid connections being restricted so as not to interfere with the operation of said differential fluid pressure means in moving said distributing piston.

2. A fluid control valve, comprising a body having a chamber therein, a fluid distributing piston slidably disposed in said chamber, an inlet port 40 in said body, a distributing port in said piston at one end communicating at all times with said inlet port, a pair of spaced outlet ports in said body communicating with said chamber in the path of movement of the other end of said distributing port, differential fluid pressure means to move said distributing piston to bring said distributing port into communicating relation with the desired one of said outlet ports, mechanism actuated by the fluid controlled to automatically center said distributing piston in a position in which it communicates with neither of said outlet ports, and a continuous fluid pressure connection between the fluid controlled and said mechanism for providing pressure fluid for actuating said mechanism, said fluid connections being restricted so as not to interfere with the operation of said differential fluid pressure means in moving said distributing piston.

3. A fluid control valve comprising a body having a chamber therein, a fluid distributing piston slidably disposed in said chamber, an inlet port in said body, a distributing port in said piston, one end thereof communicating at all times with said inlet port and at the other end terminating at a sliding surface of said piston, a pair of spaced outlet ports in said body communicating with said chamber in the path of movement of said distributing port, said piston being movable to bring said distributing port successively into communication with said outlet ports, said piston having a central position in which said distributing port is between said outlet ports and in communication with neither of them, restricted ports for providing communication between said distributing port and each end of said chamber,

pressure releasing means for each end of said chamber and communicating therewith for causing said piston to move to direct fluid from said inlet through said distributing port to one of said outlet ports or to the other depending on the pressure releasing means actuated, and fluid pressure actuated centering means at each end of said body arranged to center said piston upon closing of said pressure releasing means, said fluid pressure actuated means having restricted ports for conducting fluid pressure, said ports having communication with each end of said chamber respectively, said ports being sufficiently restricted as not to interfere with the operation of said pressure releasing means.

4. A fluid control valve comprising a body having a chamber therein, a fluid distributing piston slidably disposed in said chamber, an inlet port in said body, a distributing port in said piston, one end thereof communicating at all times with said inlet port and at the other end terminating at a sliding surface of said piston, a pair of spaced outlet ports in said body communicating with said chamber in the path of movement of said distributing port, said piston being movable to bring said distributing port successively into communication with said outlet ports, said piston having a central position in which said distributing port is between said outlet ports and in communication with neither of them, restricted ports for providing communication between said distributing port and each end of said chamber, pressure releasing means for each end of said chamber and communicating therewith for causing said piston to move to direct fluid from said inlet through said distributing port to one of said outlet ports or to the other depending on the pressure releasing means actuated, and a fluid actuated centering rod at each end of said body arranged to automatically center said piston upon closing of said pressure releasing means, said fluid actuated centering rods having actuating means having associated therewith restricted ports for conducting operative fluid, said ports having communication with each end of said chamber respectively, said ports being sufficiently restricted as not to interfere with the operation of said pressure releasing means.

5. A fluid control valve comprising a body having a chamber therein, a fluid distributing piston slidably disposed in said chamber, an inlet port in said body, a distributing port in said piston, one end thereof communicating at all times with said inlet port and at the other end terminating at a sliding surface of said piston, a pair of spaced outlet ports in said body communicating with said chamber in the path of movement of said distributing port, said piston being movable to bring said distributing port successively into communication with said outlet ports, said piston having a central position in which said distributing port is between said outlet ports and in communication with neither of them, restricted ports for providing communication between said distributing port and each end of said chamber, an auxiliary cylinder at each end of said body, an auxiliary piston in each auxiliary cylinder, means providing a communication between each end of said chamber and said auxiliary cylinders respectively, pressure releasing means for each end of said chamber and communicating therewith through said auxiliary cylinders respectively for causing said distributing piston to move to direct fluid from said inlet through said distributing port to one of said outlet ports or the other depending on the pres-

sure releasing means actuated, and centering means actuated by said auxiliary pistons under the action of the controlled fluid, upon closing of the pressure releasing means, operative to center said distributing piston.

6. A control valve comprising a body having a chamber therein, a fluid distributing piston slidably disposed in said chamber, an inlet port in said body, a distributing port in said piston, at one end thereof communicating at all times with said inlet port and at the other end terminating at a sliding surface of said piston, a pair of spaced outlet ports in said body communicating with said chamber in the path of movement of said distributing port, said piston being movable to bring said distributing port successively into communication with said outlet ports, said piston having a central position in which said distributing port is between said outlet ports and in communication with neither of them, restricted ports for providing communication between said distributing port and each end of said chamber, an auxiliary cylinder at each end of said body, an auxiliary piston in each auxiliary cylinder, means providing a communication between each end of said chamber and said auxiliary cylinders respectively, a piston rod connected to each of said auxiliary pistons projecting into said chamber, the effective area of each auxiliary piston being greater than that of its rod, pressure releasing means for each end of said chamber and communicating therewith through said auxiliary cylinders respectively for causing said distributing piston to move to direct fluid from said inlet through said distributing port to one of said outlet ports or the other, and depending on the pressure releasing means actuated, said auxiliary pistons, upon closing of the pressure releasing means, being operative under the action of the pressure fluid conducted from said chamber to said auxiliary cylinders to move said rods inwardly of said chamber to engage the ends of said distributing piston to center the same.

7. The invention as defined in claim 6 wherein the pressure releasing means for each end of the first chamber comprises a port in each piston rod for conducting pressure fluid from the respective ends of the chamber to the respective auxiliary cylinders, and pressure releasing valves having communication with the auxiliary cylinders respectively.

8. The invention as defined in claim 5 wherein there is provided a vent at the inner end of each auxiliary cylinder for permitting free movement of the auxiliary pistons under the action of pressure fluid from the ends of the chamber.

9. A control valve comprising a body having a chamber therein, a fluid distributing piston slidably disposed in said chamber, an inlet port in said body, a distributing port in said piston, at one end thereof communicating at all times with said inlet port and at the other end terminating at a sliding surface of said piston, a pair of spaced outlet ports in said body communicating with said chamber in the path of movement of said distributing port, said piston being movable to bring said distributing port successively into communication with said outlet ports, said piston having a central position in which said distributing port is between said outlet ports and in communication with neither of them, an auxiliary cylinder at each end of said body, an auxiliary piston in each auxiliary cylinder, the cross-sectional area of each auxiliary piston being less than that of said distributing piston, a piston rod connected to each

of said auxiliary pistons projecting into said chamber, the effective area of each auxiliary piston being greater than that of its rod, fluid conducting means for continuously conducting fluid to be distributed under pressure into said auxiliary cylinders to urge the pistons therein inwardly, the respective piston rods connected to said pistons, when in their inner positions, engaging the ends of said distributing piston to hold the same in its said central position, fluid conducting means operatively connected with the ends of said chamber, respectively, on opposite sides of said distributing piston for conducting fluid with respect to the ends of said chamber, and valve means in said fluid conducting means for controlling the flow of fluid therethrough so as to cause the overcoming of the centering action of said auxiliary pistons to move said distributing piston to move to direct fluid from said inlet through said distributing port to one of said outlet ports or the other as desired.

10. A fluid control valve comprising a body having a chamber therein, a fluid distributing piston slidably disposed in said chamber, a pair of outlet ports in said body communicating with said chamber, an inlet port in said body communicating with said chamber, a distributing port in said piston for directing fluid from said inlet to one of said outlet ports in one position of said piston and to the other of said outlet ports in another position of said piston, there being an intermediate position of said piston at which inlet fluid is directed to neither of said outlet ports, differential fluid pressure means arranged to be rendered active to actuate said piston to direct fluid to said outlet ports as desired and arranged to be rendered inactive following being rendered active, and fluid actuated means operable upon said differential pressure fluid means being rendered inactive to dispose and maintain said distributing piston in its intermediate position, said fluid actuated means being arranged to be operative against the ends of said distributing piston to move the same to said intermediate position.

11. A fluid control valve comprising a body having a chamber therein, a fluid distributing piston slidably disposed in said chamber, a pair of outlet ports in said body communicating with said chamber, an inlet port in said body communicating with said chamber, a distributing port in said piston for directing fluid from said inlet to one of said outlet ports in one position of said piston and to the other of said outlet ports in another position of said piston, there being an intermediate position of said piston at which inlet fluid is directed to neither of said outlet ports, a pair of auxiliary cylinders, means to conduct pressure fluid to said auxiliary cylinders, a piston in each of said auxiliary cylinders, means connected to said auxiliary pistons for positioning said distributing piston at said intermediate position, and controlled means to conduct pressure fluid to opposite ends of said chamber to act against the ends of said distributing piston to move the same to the desired one of said fluid directing positions.

12. The invention as defined in claim 11 wherein the pressure fluid for acting on said distributing piston and said auxiliary pistons is the fluid controlled and the cross sectional area of each auxiliary piston is less than that of said distributing piston.

13. A valve for controlling pressure fluid comprising a body having a chamber therein, a fluid

distributing piston slidably disposed in said chamber, an inlet port in said body, a distributing port in said piston, one end thereof communicating at all times with said inlet port and at the other end terminating at a sliding surface of said piston, a pair of spaced outlet ports in said body communicating with said chamber in the path of movement of said distributing port, said piston being movable to bring said distributing port successively into communication with said outlet ports, said piston having a central position in which said distributing port is between said outlet ports and in communication with neither of them, restricted ports for providing communication between said 10 distributing port and each end of said chamber, an auxiliary cylinder at each end of said body, a pressure fluid connection between the fluid controlled and each auxiliary cylinder, an auxiliary piston in each auxiliary cylinder, means for applying a differential fluid pressure to opposite ends of said distributing piston for causing said distributing piston to move to direct fluid from said inlet through said distributing port to one of said outlet ports or the other depending on the one of said means actuated, and centering means actuated by said auxiliary pistons under the action of the controlled fluid through said pressure fluid connection, upon the rendering inoperative of said means for applying a differential fluid pressure operative to center said distributing piston, said centering means comprising piston rods connected to said auxiliary pistons and extending into the ends of said chamber respectively for operative centering contact with said distributing piston.

14. The invention as defined in claim 5 wherein the pressure releasing means for each end of the first chamber comprises a port in each piston rod for conducting pressure fluid from the respective 25 ends of the chamber to the respective auxiliary cylinders, and pressure releasing valves having communication with the auxiliary cylinders respectively.

15. The invention as defined in claim 6 wherein 30 there is provided a vent at the inner end of each auxiliary cylinder for permitting free movement of the auxiliary pistons under the action of pressure fluid from the ends of the chamber.

16. A control valve for distributing fluid under 35 pressure comprising a body having a chamber therein, a fluid distributing piston slidably disposed in said chamber, a pair of outlet ports in said body communicating with said chamber, an inlet port in said body communicating with said chamber, a distributing port in said piston for directing fluid from said inlet to one of said outlet ports in one position of said piston and to the other of said outlet ports in another position of said piston, there being an intermediate position 40 of said piston at which inlet fluid is directed to neither of said outlet ports, differential fluid pressure means arranged to be rendered active to actuate said piston to direct fluid to said outlet ports as desired and arranged to be rendered inactive following being rendered active, and fluid actuated means, projectable into opposite ends of said chamber and engageable with said piston, operable upon said differential pressure fluid means being rendered inactive to dispose and maintain 45 said distributing piston in its intermediate position.
